PAGE 2

Fig. 5

Figure 1 is a front elevational view of a display case for wallets and similar articles showing my new design;

Fig. 5 is an enlarged rear perspective view thereof with two drawers in partly open position; and

I claim:

The ornamental design for a display case for wallets and similar articles, substantially as shown.
